Primary Examiner — Susan Bennett Hattan*Assistant Examiner* — Leanne Was(74) *Attorney, Agent, or Firm* — Andrus Intellectual Property Law, LLP(57) **CLAIM**

I claim the ornamental design for a tamper evident device, as shown.

DESCRIPTION

FIG. 1 is a front left perspective view of a tamper evident device;

FIG. 2 is a front view of the tamper evident device;

FIG. 3 is a left side view of the tamper evident device, wherein the right side view is a mirror image thereof; and,

FIG. 4 is a top view of the tamper evident device.

The broken line(s) which define the bounds of the claimed design form no part thereof.
